UNITED STATES PATENT OFFICE.

NICHOLAS I. WOOLSEY, OF NEW YORK, N. Y.

COIN-CONTROLLED VENDING-MACHINE.

SPECIFICATION forming part of Letters Patent No. 628,510, dated July 11, 1899.

Application filed July 6, 1898. Serial No. 685,251. (No model.)

To all whom it may concern:

Be it known that I, NICHOLAS I. WOOLSEY, of the city of New York, (Cedarhurst,) borough of Queens; in the county of Queens and State of New York, have invented a new and Improved Coin-Controlled Vending-Machine, of which the following is a full, clear, and exact description.

The object of the invention is to provide a new and improved coin-controlled vending-machine, more especially designed for vending lead-pencils and other articles in stick form, the machine being simple and durable in construction and arranged to contain a large number of articles to obviate frequent refilling.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a sectional side elevation of the improvement on the line 1 1 in Fig. 3. Fig. 2 is a similar view of the same on the line 2 2 in Fig. 3. Fig. 3 is a sectional front elevation of the improvement on the line 3 3 in Fig. 1; and Fig. 4 is a plan view of the slide.

The improved coin-controlled vending-machine is provided with a suitably-constructed casing A, in which are arranged a series of chutes B B' B² B³ B⁴, located one in front of the other and each adapted to contain lead-pencils or other articles C to be sold, the chutes being arranged in such a manner that the articles in each chute rest on top of one another, as is plainly indicated in Fig. 1.

The lower ends of the chutes B B' B² B³ B⁴ terminate on the peripheral surface of a wheel D, secured on a transverse shaft E, mounted to turn in suitable bearings in the casing A, the said chutes being adapted to deliver the pencils or like articles into recesses D', formed on the peripheral surface of the wheel D, the recesses being preferably placed an equal distance apart, as shown in Fig. 1.

By the arrangement described it is evident that when the wheel D rotates in the direction of the arrow a', as indicated in Fig. 1, then the recesses D' are filled successively

with lead-pencils from the rearmost chute B, as this chute registers first and successively with the several recesses D'. The lead-pencils or other articles C after passing the front chute B⁴ drop out of the corresponding recess into a delivery-spout F, formed in the front of the casing and leading to the outside thereof to a stop G, from which the lead-pencil may be removed by the buyer.

When the machine is in operation and the chute B has been exhausted of its articles, then the next chute B' commences to deliver the articles to the wheel D, and when this chute is exhausted the next following chute supplies the articles, and so on until the chutes are successively emptied of their articles.

In order to show that the machine is empty and in order to prevent an intended buyer from dropping a coin into the machine, I provide the front of the chute B⁴ with a glass window B⁵ for indicating whether the chute B⁴ is still filled or empty. In the former case the machine is in condition to sell the articles; but when no pencils are visible at the window B⁵ the machine is empty.

On the shaft E is secured a coin-operated wheel H, formed in its periphery with notches H', into the lowermost one of which is adapted to pass a coin I, as is plainly shown in Fig. 2, said coin being also adapted to pass into a slot J' in a slide J, fitted to slide laterally in the casing A at one side of the machine, as is plainly indicated in Fig. 3. The slide J is formed at its outer end with a suitable handle J², adapted to be pressed inward by the buyer, so that the coin I moves with the slide, and as it engages one of the notches H' it turns the wheel H, and with it the wheel D, in the direction of the arrow a'. When the coin I is in the slide and wheel, it stands on its edge, the lower portion resting on the false bottom A' of the casing, and when the slide J is moved rearwardly the opening J' in the slide passes the rear end of the false bottom A' and registers with the opening A², so that the coin drops through the slot J' and out of engagement with the notch H' in the wheel H. The coin passes into position in the slide and wheel, as shown in Fig. 2, from a coin-chute K, secured in the casing at one side thereof, the upper end of the chute opening at the

front of the casing to permit a buyer to drop a coin into the chute. The coin drops into the chute and then passes in a vertical position into the registering slots J' and H', the 5 lower end of the coin resting on the false bottom A' to permit the operator to turn the wheel on pushing the handle J² inward. When the coin drops out of the slide and through the opening A², it passes into a drawer L, 10 emptied from time to time by the owner of the machine.

In order to lock the wheel H in place after the slide J is pushed inward, as previously explained, I provide a spring N, extending 15 over the peripheral surface of the wheel and secured at its rear end at N' to the casing. The free end of the spring engages an opening J³ in the slide J and presses on the forward wall of the opening to hold the slide 20 normally in an outermost position. Near the free end of the spring N is arranged a tooth N², adapted to engage one of the notches H' at the time the slide J moves into a rearmost position and the coin I drops out of the slide, 25 as previously explained. When this takes place and the operator releases the pressure on the handle J², then the slide immediately returns to its former position without, however, rotating the wheel H, as the slide and 30 wheel are now disconnected. A spring N³, secured to the rear end of the casing A, presses with its free end on the rear end of the slide J to assist in returning the slide to its former outermost position, and this spring N³ is provided with a tooth N⁴, normally engaging one 35 of the recesses H' to lock the wheel H against accidental rotation—that is, when the slide is not moved.

Having thus fully described my invention, 40 I claim as new and desire to secure by Letters Patent—

1. A coin-controlled vending-machine, provided with a revoluble wheel formed in its peripheral surface with recesses adapted to receive the articles to be vended, a notched actuating-wheel connected with the revoluble wheel, a slide having a slot adapted to register with a notch in the said notched wheel, a chute for delivering a coin to the said registering notch in the wheel and the slot in the slide, and springs controlled by the said slide and adapted to engage the said notched wheel to lock the wheel against accidental rotation, substantially as described.

55 2. A coin-controlled vending-machine provided with a revoluble wheel formed in its peripheral surface with longitudinal recesses each adapted to receive a single article to be vended, a series of chutes located one in front 60 of the other and each adapted to contain the articles placed one upon the other, the chutes opening upon the peripheral surface of the wheel at different places to register with the

said recesses, a notched actuating-wheel connected with the revoluble wheel, a slide having a slot adapted to register with a notch in the said notched wheel, a chute for delivering a coin to the registering notch in the wheel and the slot in the slide, springs controlled by the said slide and adapted to engage the said notched wheel to lock the wheel against accidental rotation, the said revoluble wheel when actuated rotating in direction of the front of the machine, the chutes being emptied successively from the rear to the front, and means 75 for viewing the contents of the chute at the front of the machine, substantially as shown and described.

3. A coin-controlled vending-machine provided with a revoluble wheel formed in its 80 peripheral surface with longitudinal recesses, chutes for filling said recesses with the articles to be vended, a notched wheel on the shaft of said revoluble wheel, a slide having a slot adapted to register with one of the 85 notches in the said notched wheel, a chute for delivering a coin to the said registering notch in the wheel and the slot in the slide, and springs controlled by the said slide and each having a tooth for engagement with notches in the said notched wheel, to lock the wheel against accidental rotation, substantially as shown and described.

4. A coin-controlled vending-machine, provided with a notched actuating-wheel, a slide 95 having a notch adapted to receive a coin adapted to engage a registering notch in said wheel, and springs controlled by the said slide, and each having a tooth for engagement with notches in said wheel, to lock the wheel against 100 accidental rotation, substantially as shown and described.

5. A coin-controlled vending-machine provided with a revoluble wheel formed in its peripheral surface with recesses adapted to receive the articles to be vended, a notched wheel on the shaft of the said revoluble wheel, a slide having a slot adapted to register with one of the notches in said wheel, a chute for delivering a coin to the said registering notch in the wheel 110 and the slot in the said slide, a spring secured at its rear end to the casing and extending over the peripheral surface of the wheel, the free end of the spring engaging an opening in the slide and serving to hold the slide normally in an outermost position, a spring secured to the rear end of the casing and pressing with its free end on the rear end of the slide, the said springs being provided with teeth for engagement with notches in the 115 wheel, substantially as shown and described.
